US00D912713S

(12) **United States Design Patent** (10) **Patent No.:** **US D912,713 S**
Moran et al. (45) **Date of Patent:** **** Mar. 9, 2021**

(54) **OIL FILTER REMOVAL DEVICE**

(71) Applicants: **Kevin Francis Moran**, South Lyon, MI (US); **Elliott Heinrich**, Grand Rapids, MI (US)

(72) Inventors: **Kevin Francis Moran**, South Lyon, MI (US); **Elliott Heinrich**, Grand Rapids, MI (US)

(**) Term: **15 Years**

(21) Appl. No.: **29/709,182**

(22) Filed: **Oct. 11, 2019**

(51) LOC (13) Cl. **15-09**

(52) U.S. Cl.

USPC **D15/150**; D8/21

(58) **Field of Classification Search**

USPC D8/21; D15/150, 151, 152; D23/209, D23/213

CPC .. B01D 2201/24; B25B 27/0042; F16N 33/00

See application file for complete search history.

(57) **CLAIM**

The ornamental design for an oil filter removal device, as shown and described.

DESCRIPTION

FIG. 1 is a top-front perspective view of the oil filter removal device;

FIG. 2 is a bottom-rear perspective view thereof;

FIG. 3 is a different top-front perspective view thereof;

FIG. 4 is a top-rear perspective view thereof;

FIG. 5 is a front view thereof;

FIG. 6 is a bottom view thereof;

FIG. 7 is a top view thereof;

FIG. 8 is a left side view thereof;

FIG. 9 is a right side view thereof; and,

FIG. 10 is a rear view thereof.

The broken lines are included for the purpose of illustrating unclaimed features of the oil filter removal device and form no part of the claimed design.

1 Claim, 8 Drawing Sheets
